MODULAR SHELVING ASSEMBLY

Sydney W. Jentzen, Bloomfield Hills, Mich., assignor to Jentzen-Miller Company, Troy, Mich., a corporation of Michigan

Filed May 16, 1961, Ser. No. 110,582

4 Claims. (Cl. 108—158)

This invention relates to shelving and more particularly to a shelving assembly or room divider construction.

It is the object of the present invention to provide a modular form of shelving assembly, using a series of similarly shaped upright studs, which are suitably spaced and arranged to provide support members together with shelving spacers interposed between pairs of said studs and with means for simply, yet fixedly securing said shelving to the studs to thus define a shelving assembly.

It is another object of the present invention to provide a novel form of stud construction of an extruded formation, with elongated undercut slots in opposed walls thereof of providing a means by which shelving supporting fasteners may be interlocked and secured and variably adjusted, as desired.

It is a further object of the present invention to provide a modular form of shelving assembly employing a series of uniform mounting studs in predetermined spaced relation and interposed between the said studs a series of horizontally disposed spacing elements which may be shelves or cabinets, or the like, for providing an interesting room divider, or other shelving arrangement for display or other purposes.

The present invention also has for its object the construction of a novel form of fastener by which shelving and cabinets may be easily secured and adjusted with respect to the supporting studs, as desired.

These and other objects will be seen from the following specification and claims in conjunction with the appended drawings, in which:

FIG. 1 is a front perspective view of the present shelving or room divider assembly.

FIG. 2 is a horizontal section taken through the lower portion of the assembly shown in FIG. 1, and partially broken away, for illustration.

FIG. 3 is a fragmentary section taken on line 3—3 of FIG. 2.

FIG. 4 is a fragmentary section taken on line 4—4 of FIG. 2.

FIG. 5 is a plan view of a fastener nut employed.

FIG. 6 is a section taken on line 6—6 of FIG. 5.

FIG. 7 is a fragmentary elevational view of the lower end of one of the studs, on an enlarged scale and illustrating the mounting of the adjustable foot therefore.

FIG. 8 is a section taken on line 8—8 of FIG. 7.

It will be understood that the above drawings illustrate merely a preferred embodiment of the invention and that other embodiments are contemplated within the scope of the claims hereinafter set forth.

Referring to the drawings, the present room divider, or shelving assembly, is of a modular type of construction and may be extended laterally and enlarged as desired by the application of suitable shelving or by cabinets interposed between a series of parallel spaced upright supporting studs generally indicated at 11.

Each of the studs 11 are preferably formed of an extruded metal such as aluminum, though not limited to aluminum and have formed throughout their length and arranged upon opposite sides thereof the continuous longitudinally extending dovetailed type slots 12, which provide the interlocking means for mounting shelving and cabinets as hereinafter described.

The studs 11 thus include the inwardly directed flanges

2

13 arranged upon opposite sides of the reduced portion of the dovetail apertures 12, said flanges being the retaining means for the locking nuts hereinafter described, and which nuts are adjusted longitudinally within the said elongated slot 12.

The opposing right-angularly related sides of the said studs are plane as indicated at 14, FIG. 8.

In the preferred embodiment of the invention, by way of illustration in FIG. 1 there is shown the horizontally disposed shelf 15 which is interposed between the respective upright pairs of studs 11 and adjustably, yet fixedly secured thereto by the fastening mechanism about to be described.

The cabinet assembly is also generally indicated at 16 in FIG. 1, also interposed between opposed pairs of parallel upright studs 11 and secured thereto. Each of the upright studs 11 has mounted at its lower end an adjustable foot for the purpose of properly leveling the supporting structure. For this purpose, the said studs at their lower ends have central interiorly threaded bores 17 adapted to threadedly and adjustably receive the threaded studs 18, which project thereinto.

Each of the said studs carries a hex-shaped collar 19 arranged directly below the lower ends of the respective studs. Stud 18 also includes a rivet head 20 in order to retainingly engage the plastic or Bakelite supporting foot 21, as best illustrated in FIG. 7.

The specific means by which the shelving or cabinets are secured within and between the supporting studs 11, is best illustrated in FIGS. 2, 3, 4. For illustration with respect to FIG. 3, a portion of the cabinet 15 is fragmentarily shown and has formed inwardly from its outer end portions adjacent the corners thereof the elongated bores 23 within which nest the elongated shanks 22 of the fasteners 24, which are flattened for sliding cooperative engagement with the outer flattened surfaces of the flanges 13, which form a portion of the studs 11, as best illustrated in FIGS. 2, 3 and 4.

Suitable threaded stud 25, exteriorly knurled for ease in operation, is projected transversely through a central aperture formed in the head portion 24 of the fastener for cooperative projection through the threaded bore 26 of the securing nuts 27, which are of T-form in cross section.

The said nuts 27 are of parallelogram form with parallel tapered end portions 28 and of such widths as to fit between the opposed flanges 13 by which the said nuts may be introduced into the dovetailed slots 12 as shown in FIG. 4, in dotted lines. After projection between the flanges 13, the nut 28 is rotated 90 degrees to the solid line position shown in FIG. 4, and the stud 25 is tightened so that the one-surface of the nut 28 operatively engages the interior wall portion corresponding to the flanges 13 by which the shelving 15 is secured in vertically adjusted position with respect to the corresponding stud 11.

Each of the nuts 28 also include a central cylindrical shank 30 which cooperatively projects between the corresponding flanges 13 and which is longitudinally slit from opposite sides as at 31 in order to provide a small expansion during the fastening operation.

In the preferred embodiment of the invention, the studs 25 are in the nature of Allen screws and have a hex-opening 29 to facilitate the application of an Allen wrench for the tightening or loosening thereof.

Referring to FIG. 1, a pair of cabinets are generally indicated at 16, as interposed between corresponding pairs of upright studs 11, and are fixedly secured thereto in the same manner as above described in conjunction with the securing of the shelving elements 15 with respect to the studs 11. This construction is further illustrated at FIG. 2, wherein it is seen that the lefthand stud 11 employs a single vertically adjustable nut, a single securing Allen

screw 25 and the pair of substantially aligned fastener assemblies 22—24, whose heads are in overlapped registry to receive the single fastener 25.

Referring to FIGS. 1 and 2, the cabinet 16 includes the upright rear wall 32 which is interposed between the rear opposed pairs of studs 11 and suitably secured thereto adjacent the top and bottom of the said rear panel as by the similar set of fastening elements 22—24, best illustrated in FIG. 2 at the upper left side. All that is required is that a suitable bore 23 be formed into the longitudinal end portions of the respective panel 32 adjacent its upper and lower edges, after which the shafts 22 of the locking fasteners are projected thereinto with the flattened head portions 24 extending outwardly therefrom for registry with the slotted rear wall of the stud 11. Here the assembly is the same as above described and the back panel 32 is fixedly, yet adjustably secured to the corresponding rear studs 11 in the manner herein above described.

The cabinet 16 also shows the upright end walls 33 which are normally merely mounted upon the respective top and bottom shelves which define the cabinet 16 and suitably secured thereto.

The upper of the two cabinets 16 has front panel 34 which serves as a door and is longitudinally hinged at its inner longitudinal edge as at 35 to a front portion of the support element 15 which forms a part of the cabinet corresponding to the shelving 15, also shown in FIG. 1. Here a suitable magnetic catchplate 36 is provided on the inner surface of the panel 34 for registry with the corresponding metal plate 37, on the top shelving element of the said cabinet when the panel 34 is in upright position.

The said door panel 34 is retained in the open horizontal position shown by a pair of flexible stays 38, anchored at 39 to interior portions of the end walls 33 and at the respective other ends secured as of 40 to outer portions of the panel 34, for illustration.

The present construction thus defines a modular shelving arrangement employing a simplified means by which a series of horizontally disposed shelving elements, or cabinet elements may be interposed and adjustably secured to the respective pairs of studs 11 within and between which the said members are mounted.

Should it be desired to effect a vertical adjustment of an individual shelf 15, such as either the uppermost shelves, for illustration, all that is necessary is to merely loosen the Allen studs or screws 25 and raise or lower the shelving 15, as desired, after which the studs are re-secured so that the T-nuts lock within the dovetail grooves 12 for securing the shelving in any desired vertical position.

The flattened heads of fasteners 24 are offset relative to the axes of the fastener shanks 22. Said fasteners are thus reversible and thus may be used in one of two 180 degree positions of assembly for aligning a series of shelving.

In the preferred embodiment, all the bores 23 are at a fixed distance from the edge of the shelving, such as $5\frac{1}{8}$ of an inch, for illustration. Accordingly the offset relationship of the flat head with respect to the shank permits an adjustability factor in the assembly of the shelving.

The securing nuts 27 include on their rear surfaces, one or more dimples, or a coating 41 of a resilient plastic material such as vinyl. By this construction, the nut may be frictionally retained in a predetermined longitudinally adjustable position in the stud 11. This assists in the assembly of the shelving and prevents the nuts 27 from moving accidentally from a predetermined location yet leaves the nuts manually adjustable as desired.

Having described my invention, reference should now be had to the following claims:

I claim:

1. A shelving assembly comprising transversely spaced pairs of spaced upright studs mountable upon a support surface, each stud having formed in its front and rear face throughout its length, an elongated undercut slot, a horizontally disposed shelving panel interposed between and spacing apart said pairs of studs, mounting keys, each including an elongated shank projected longitudinally into and frictionally nested within corresponding bores in the ends of said panel adjacent its front and rear, said keys including flattened heads extending longitudinally of the ends of said panel and bearing against the respective faces of said studs overlying said slots, T-shaped nuts nested in said slots and longitudinally adjustable therein, and a fastener extending through each head threaded into a nut for frictionally securing the same within its slot.

2. A shelving assembly comprising transversely spaced pairs of spaced upright studs mountable upon a support surface, each stud having formed in its front and rear face throughout its length, an elongated undercut slot, a series of horizontally disposed shelving panels interposed between and spacing apart said pairs of studs, the securing of each of said panels to said studs including mounting keys, each including an elongated shank projected longitudinally into and frictionally nested within corresponding bores in the ends of each panel adjacent its front and rear, said keys including flattened heads extending longitudinally of the ends of said panel and bearing against the respective faces of said studs overlying said slots, T-shaped nuts nested in said slots and longitudinally adjustable therein, and a fastener extending through each head threaded into a nut for frictionally securing the same within its slot.

3. In the shelving assembly of claim 1, the head of each key being displaced from the longitudinal axis of its elongated shank, so that the key may be selectively used in one of two 180 degree related positions.

4. The shelving assembly of claim 1, and a layer of resilient material on the rear surface of said nuts for frictional temporary retaining engagement with said studs.
